Barclay White,
by his Attorneys,
Howard Howam

UNITED STATES PATENT OFFICE.

BARCLAY WHITE, OF LANSDOWNE, PENNSYLVANIA.

REINFORCED CONCRETE CONSTRUCTION.

1,389,404.

Specification of Letters Patent. Patented Aug. 30, 1921.

Application filed June 18, 1918. Serial No. 240,616.

To all whom it may concern:

Be it known that I, BARCLAY WHITE, a citizen of the United States, residing in Lansdowne, Pennsylvania, have invented 5 certain Improvements in Reinforced Concrete Construction, of which the following is a specification.

My invention relates to concrete or similar plastic floor construction, and one object of my invention is to provide a series 10 of hollow blocks of concrete or similar plastic material, or of concrete combined with a hollow center of stiff paper, wall-board, wood, or similarly available substance capable of performing a similar function, of such shape, character and construction as to serve as a filler between reinforced concrete joists or beams spanning bays or floor spaces in building construction.

20 The improved hollow filling blocks forming part of my invention have top and bottom surfaces substantially parallel with each other; the bottom surfaces forming the ceiling of one story and the top surfaces, with 25 or without the addition of a special surfacing material which, when used, is preferably applied during manufacture, forming the floor of the story above; such blocks having substantially vertical side walls with 30 flanges entirely surrounding the same and preferably disposed at the base of the blocks when the latter are set in place. These flanges are designed to contact with each other when the blocks are set upon 35 suitable staging or supports which underlie the meeting edges of the flanges whereby I am able to eliminate the necessity for continuous centering or forms, and the spaces between the hollow blocks above the flanges 40 of the same receive concrete to form joists or beams in which may be embedded suitable metallic reinforcement.

A further object of my invention is to provide a suitable internal form of paper or 45 similar fibrous material which may serve as a core support for concrete poured around the same in preparing the blocks, so that the block structures when finished will be hollow, light, strong, dry, and fireproof, 50 with the additional advantages of being a poor conductor of heat or sound; or such core may be used independently of complete blocks in forming a floor or ceiling, as hereinafter set forth.

55 A further object of my invention is to provide suitable reinforcing means for the sev-

eral walls of the blocks so that they will be strong enough to safely support the loads imposed upon them when incorporated in the floor construction.

60 A still further object of my invention is to provide a hollow precast or preformed unit which may be quickly and easily placed upon temporary staging and which, after the narrow spaces or grooves between the 65 block units are filled with concrete laid over metal bars or other reinforcement, will not only act in assisting to carry the compressive stresses caused by the beam or plate action taking place in the floor when the 70 latter is loaded after removal of the staging, but may furnish a hard, smooth and durable tile-like floor which can be walked upon immediately after the concrete is poured in the spaces between the blocks and before such 75 concrete hardens.

These and other features of my invention are more fully described hereinafter, reference being had to the accompanying drawings, in which:

80 Figure 1, is a cross sectional view of a mold or form in which my improved blocks may be made; such view showing also reinforcing material for the several walls of such blocks, and the inserted core.

85 Fig. 2 is a view, partly in elevation and partly in vertical section, of a finished block.

Fig. 3, is a cross sectional view of a floor illustrating the manner in which the blocks are set in place and receive concrete in the 90 spaces between the same.

Fig. 4, is a view somewhat similar to Fig. 3, but illustrating a modified arrangement within the scope of my invention.

Fig. 5, is a perspective view showing the 95 blocks in place and the floor in course of construction, and

Figs. 6, 7 and 8, are sectional views illustrating modified arrangements within the scope of my invention.

100 In preparing the improved blocks 1 forming one part of my invention, I preferably provide a form such as illustrated in Fig. 1, which may comprise a bottom 2, and side walls 3 hinged to said bottom at 4, and 105 having inwardly projecting portions 3^a and 3^b for a purpose to be described, and within the same I dispose a basket-like reinforcement of wire 5 preferably having foot members 6 whereby it may be spaced from the 110 bottom of the form. Upon the bottom of such form and to a depth sufficient to fully

cover the portion 5^a of the reinforcement, I pour concrete when making the block, and this portion or layer of the concrete may be of a special character, containing special 5 coloring matter, or a suitable hardening agent, if desired, since the portion thus formed is at the top and may become the floor surface when the block is built into place in a platform or floor, as indicated in 10 Figs. 3 and 5.

In order to make this portion of the concrete; that is to say, the part which becomes the floor surface when the block is built into place, of a suitable and preferably definite 15 thickness, I may introduce suitable means that will level the same, such for instance as an insertible block (not shown) designed to be centrally disposed with respect to the mold and to be pressed down upon the layer 20 of concrete in the bottom of the same, which subsequently becomes the floor surface. The use of such leveling means is not essential, however, and when the layer of concrete has set to a certain extent I introduce a permanent 25 core member, indicated at 10, which is preferably made of waterproof paper, or other similarly available material capable of performing the same function and which may comprise an outer shell 10^a, with a series 30 of partition members 10^b, 10^c; preferably disposed at right angles to each other and serving as a reinforcing support to prevent sagging or bulging of the outer walls of such core due to the weight of the concrete 35 employed during the process of making the blocks. After the core has been set in place, an additional metal reinforcing layer is preferably placed over the same which will be disposed in the flanged bottom portion of the 40 finished block, and such reinforcement may be of woven wire material, indicated at 5^b. Concrete is then poured around the sides of the core, filling the space between the same and the form and covering the top of the 45 core and said wire reinforcement 5^b.

The top surface of the finished concrete mass within the mold may then be trued with a suitable float, and this surface may be smooth or rough, depending whether or not 50 it will form the finished surface of the ceiling, or is to receive a coat of plaster. In the former instance, it may be desirable to finish it off with a thin layer of a mixture of materials different from the rest of the block 55 in order that the finished ceiling shall be as smooth as possible, and coloring matter may be introduced if desired.

The casting of these blocks is preferably done on a vibrating table to eliminate air 60 bubbles and insure a dense homogeneous mass in the walls of the same.

In order to provide means whereby the concrete or plastic blocks 1 may be readily handled, the side walls 3 of the form may 65 have inwardly disposed projections 3^a and 3^b

secured to the inner surface of the same, which projections are adapted to form apertures or recesses 1^a and 1^b in the side walls of said molded blocks whereby they may be easily picked up and carried, and these recesses or apertures will serve the further purpose of keying the poured concrete forming the joists or beams, to the said blocks. If desired, a plurality of these recesses may be provided in a plurality of planes, as 70 clearly illustrated in the drawings, and the central recesses 1^a may be larger, if desired. 75

After the blocks have been finished, set, and if desired, dried, they may be removed from the form in which they were poured 80 or cast, and then placed upon suitable supports, as indicated in Figs. 3, 4 and 5. Then, after suitable reinforcing means such as the bars 12 have been introduced into the spaces between the blocks, concrete or other 85 plastic material 13 is introduced therein. This concrete may be finished flush with the upper surface of the blocks; the latter forming part of the floor, as indicated in Figs. 3 and 5, or the concrete may entirely cover the 90 blocks, as shown in Fig. 4, as may be desired. In either instance additional flooring material may be placed upon the upper surface, if desired.

Should it be desired to use a floor of this 95 character for heavy, concentrated or impact loads, the thickness of and the amount of reinforcement in the top portion of the block; that is to say, the portion which is at the bottom in the mold during the pouring 100 or casting of the block may be increased, or vertical stiffening webs, preferably of concrete, may be introduced into the hollow portion occupied by the core.

The sides of the form illustrated in Fig. 105 1, have hinges 4 at their connection with the bottom, and such sides are preferably arranged to come together on diagonal lines with catches or pins 14 at the four upper corners adjacent the portion forming the 110 flange of the block in order to aid in quick assembly and disengagement.

In Figs. 6 and 7, I have illustrated modified arrangements within the scope of my invention, in which I have utilized a core of 115 pasteboard or similarly suitable material such as shown in Figs. 1 and 2, within the hollow block. Thus in Fig. 6, two slabs of concrete are indicated at 15 and 15^a; the slab 15 constituting the upper or tread portion, and the slab 15^a constituting the lower or ceiling portion and being relatively larger than the slab 15, substantially to the same extent that the flanges of the hollow block are larger than the tread portion of the 120 same. In this arrangement, each slab will be suitably reinforced by a section of reticulated metal 16, and in each instance portions 16^a of the reinforcement will extend beyond the same, as clearly illustrated. In 130

use, a hollow core portion 10 is placed between the same, and thereafter the projecting portions 16^a of the reinforcements are suitably tied together by wire strands 17; 5 the tying means lying within the subsequently applied mass of concrete 13^a to form the joist or beam between the sides of the core and the edges of the top slab. Any other suitable means of permanently securing the top and bottom slab and the filler between the same may be used.

In the structure shown in Fig. 7 the top slab is omitted and the core may be simply set into or attached to the bottom slab 15^a, 15 or even set directly on the staging without the use of a bottom slab. In the arrangement shown, the bottom slab may be cast with respect to the core so that the contacting edges of the latter are connected to the 20 slab to an extent sufficient to insure that they will be carried together for convenience of placement in the floor, after which concrete 13^b is poured between and over the cores to form the completed floor construction. If 25 desired the core may be tied to the slab by wire connections 18.

It is also within the scope of my invention to use a precast floor filler or block made with the use of a removable core so that 30 such block, when in place, will be open on the side forming the ceiling surface; giving a recessed or cellular appearance instead of the continuous ceiling surface, such form of block being shown in Fig. 8. If desired, 35 the openings or cells of such form of block could be covered with expanded metal and plaster, or any other means of producing a flat ceiling.

It is to be understood that wherever reference is made herein to the top wearing 40 surface of the blocks, it is intended that this wearing surface may form either the finished, or the under flooring of the building, since such blocks may be covered with cement, wood, composition or other top 45 surfacing material or means if and as desired.

I claim:

1. In floor construction, the combination 50 of filler members comprising relatively thin-walled, hollow blocks of hardened plastic material with an internal form of fibrous material supporting the walls of said block; the walls of said block being apertured at intervals and the internal support serving to 55 close the inner ends of said apertures, and re-

inforced concrete beams disposed at right angles to each other and inclosing said hollow block filler members; the latter being arranged to provide a wearing surface at the top.

2. In floor construction, the combination 60 of filler members comprising relatively thin-walled hollow blocks of hardened plastic material with an internal form of fibrous material supporting the walls of said block; the walls of said block being apertured at intervals and the internal support serving to close the inner ends of said apertures, reinforced concrete beams disposed at right angles to each other and inclosing said hollow block filler members; the latter being arranged to provide a wearing surface at the top, and flanges entirely surrounding the 65 filler members and integral with the bottom thereof; said flanges adapted to abut on all 70 sides and provide a continuous ceiling surface.

3. As a new article of manufacture, a hollow concrete member having integral top, 75 bottom, and side walls, a fibrous supporting shell within the hollow concrete member, and vertically disposed supporting means arranged within said fibrous shell.

4. As a new article of manufacture, a hollow concrete member having top, bottom, 80 and side walls; a fibrous supporting shell within the hollow concrete member, vertically disposed supporting means arranged within said fibrous shell, and a metallic reinforcement within the walls of said hollow 85 concrete member and entirely surrounding the fibrous structure.

5. As a new article of manufacture, filler 90 members comprising relatively thin-walled hollow rectangular blocks of hardened plastic material with an internal form of fibrous material supporting the side and top and bottom walls of said block; said walls being apertured at intervals for the reception of 95 keying portions of concrete placed between the blocks, and the internal support serving to close the inner ends of said apertures; said filler members being arranged to provide a top wearing surface, and having 100 flanges entirely surrounding the same and integral with the bottom walls; said flanges 105 adapted to abut and provide a continuous ceiling surface.

BARCLAY WHITE.
